UNITED STATES PATENT OFFICE.

HANNAH LEOLA PERRY, OF EAST LIVERPOOL, OHIO.

HAT-BOX.

SPECIFICATION forming part of Letters Patent No. 666,352, dated January 22, 1901.

Application filed June 26, 1900. Serial No. 21,659. (No model.)

To all whom it may concern:

Be it known that I, HANNAH LEOLA PERRY, a citizen of the United States, residing at East Liverpool, in the county of Columbiana and State of Ohio, have invented a new and useful Hat-Box, of which the following is a specification.

This invention relates to folding boxes; and the particular object thereof is the provision of a knockdown box, made of paper or other light material, which may be quickly set up in position and when set up is strongly braced and has all its joints covered to exclude dirt and dust from the interior thereof.

15 The special object of the invention is the provision of a box, especially adapted for milliners' use, that will hold ladies' hats without the danger of crushing or soiling the trimmings thereof.

20 In the drawings which accompany and form a part of this specification the preferred form of construction is shown.

Figure 1 is a perspective view of the invention, showing the box set up. Fig. 2 is a perspective view of the same, showing the sides separated. Fig. 3 is a perspective view showing the box folded. Fig. 4 is a plan view of the box-blank.

Similar numerals of reference designate 30 like and corresponding parts in each of the figures of the drawings.

The box, as shown, when set up is in the form of a truncated pyramid and comprises a polygonal bottom 10, preferably square, 35 sides 11 and 11^a, and top sections 12 and 12^a, all preferably made from a single blank. The sides 11 and 11^a are trapezoidal in form, the shorter of the parallel sides forming the top edge of the box. Two opposite sides 11^a are 40 each provided along their side edges with the flaps 13, the end edges 14 of which when in set-up position are parallel with the bottom, as shown in Fig. 2. The other two opposite sides are each provided along their side edges with 45 the triangular flaps 15, each of which has a tongue 16, adapted to be inserted in the slits 17 in the sides 11^a. The top sections 12 and 12^a are preferably provided with parallel side edges 18, and their end portions are triangular-shaped. 50 One of the sections 12^a is provided with a slit 19, into which the triangular end portion of the opposite top section is adapted

to be inserted. The other two opposite top sections are provided with the securing-cords 20.

In setting up the box the sides are arranged, 55 as shown in Fig. 2, with the top sections 12^a interlocked and the flaps 13 arranged at right angles thereto, the lower edges of said flaps resting upon the bottom and the upper edges forming a rest upon which the top sections 60 12 are adapted to rest, these flaps thus forming strong braces for the box and entirely closing the side joints from top to bottom. The side sections 11 are then arranged with the flaps 15 covering the edge-joints and the 65 tongues 16 inserted in the slits 17. The top sections are overlapped to completely close the top opening, and the two upper ones 12 are fastened together by the cords 20, whereby the whole box is secured in its operative position. 70

From the above description it will be seen that a simple foldable box is provided that occupies but little space when folded and when set up is strongly braced and has all its 75 joints thoroughly covered, whereby all dirt and dust is excluded from the interior thereof.

From the foregoing it is thought that the construction, operation, and many advantages of the herein-described invention will 80 be apparent to those skilled in the art without further description, and it will be understood that various changes in the size, shape, proportion, and minor details of construction may be resorted to without departing from the 85 spirit or sacrificing any of the advantages of the invention.

Having thus described the invention, what I claim as new, and desire to secure by Letters Patent, is—

1. A knockdown box comprising a body having a bottom, folding sides connected with the bottom and provided along their meeting edges with continuous flaps extending from end to end thereof and adapted to overlap at 95 the corners, certain of said flaps having tongues adapted to detachably interlock with certain of the sides, and foldable top pieces carried at the top edges of the sides and arranged to overlap.

2. A knockdown box comprising a bottom, trapezoidal-shaped sides connected with said bottom, flaps provided along the meeting edges of said sides, certain of said flaps being adapt-

90

100

ed to fit within the box with their lower edges resting upon the bottom thereof, other of said flaps being provided with tongues adapted to engage with the adjacent sides, and top sections carried by said sides and arranged to overlap and close the top opening of the box.

3. In a knockdown box, the combination with a square bottom, of trapezoidal-shaped sides connected with the bottom, two of said opposite sides having flaps, the lower edges of which are adapted to rest upon the bottom, the other two opposite sides being provided with flaps having tongues adapted to engage with the first-named sides, and top sections carried by the sides and arranged to overlap each other and close the top opening, certain of said top sections being provided with interlocking fastening means.

4. A knockdown box comprising a bottom, sides connected with said bottom and having flaps at their side edges, the flaps of certain of said sides being arranged to rest their lower

edges on the bottom of the box when the sides are set up, and the flaps of the other sides being arranged to rest upon the outer face of 25 the first-mentioned sides.

5. A knockdown box comprising a bottom, sides connected with said bottom but disconnected from each other and having flaps at their side edges, the flaps of certain of said sides being arranged to rest their lower edges on the bottom of a box when the sides are set up, the flaps of the remaining sides being arranged to rest upon the outer face of the first-mentioned sides and have an interlocked engagement therewith.

In testimony that I claim the foregoing as my own I have hereto affixed my signature in the presence of two witnesses.

H. LEOLA PERRY.
